UNITED STATES PATENT OFFICE.

CHARLES L. PRANDONI, OF HOBOKEN, NEW JERSEY.

LEVELING INSTRUMENT FOR BUILDERS.

1,133,501.

Specification of Letters Patent.

Patented Mar. 30, 1915.

Application filed September 17, 1914. Serial No. 862,244.

To all whom it may concern:

Be it known that I, CHARLES L. PRANDONI, a citizen of the United States, residing at Hoboken, in the county of Hudson and State 5 of New Jersey, have invented certain new and useful Improvements in Leveling Instruments for Builders; and I do declare the following to be a full, clear, and exact description of the invention, such as will enable others skilled in the art to which it appertains to make and use the same.

This invention relates to improvements in combined theodolites or transits and builders levels similar to that shown in United 15 States Patent No. 461,390 granted October 13, 1891, to J. Paoli.

The object of the invention is to provide a device of this character which is very simple and accurate and which may be 20 quickly applied.

Another object is to provide a device of this character in which all the parts are mounted on the telescope and which is so constructed that by one application it is 25 rendered ready for use, and which has no parts to be taken apart.

With these and other objects in view, the invention consists of certain novel features of construction, and the combination and 30 arrangement of parts as will be hereinafter described and claimed.

In the accompanying drawings: Figure 1 represents a transverse section taken on the line 1—1 of Fig. 2; Fig. 2 is a plan view of 35 this improved instrument with parts broken out and in section; Fig. 3 is a transverse vertical section taken on the line 3—3 of Fig. 1; Fig. 4 is a longitudinal vertical section taken on the line 4—4 of Fig. 2; Fig. 5 is a plan view showing the instrument positioned for use as a builder's level; Fig. 6 40 is a side elevation of the trunnion member detached; Fig. 7 is a plan view thereof; and, Fig. 8 is a transverse section taken on the line 8—8 of Fig. 1.

In the embodiment illustrated a horizontally revoluble alidade 1 is shown of ordinary construction and adapted to turn on a central pivot on a support (not shown). 50 Removably and adjustably mounted on the ends of this alidade 1 are two forked supports 2 and 3 provided with arcuate locking levers 4 and 5. Each of the supports 2 and 3 is substantially Y-shaped and the 55 forked portion thereof has a polygonal in-

ner face to provide a plurality of spaced contact faces 6 for supporting a telescope or its trunnions with a minimum frictional engagement between them. The terminals of the arms of the forked or body portion of 60 each of the supports 2 and 3 are bifurcated and are designed to receive between the furcations thereof the opposite ends of the arcuate levers, one end of each lever being pivotally mounted between said furcations 65 on one arm of a support and the other apertured and designed to extend between the furcations of the other arm of said support, said free end of the lever and the end of the arm between which it is adapted to extend 70 being apertured to receive a locking pin 7 whereby said lever is detachably engaged with said support. The shank or stem 8 of each support is threaded and passed loosely through an aperture in the end of the alidade 75 1 being adjustably connected therewith by nuts 9 and 10 engaged with said shank on opposite sides of the alidade (see Fig. 4) whereby the bearings of said supports may be spaced varying distances from the alidade. 80 Each shank 8 is shown recessed in one side as at 11 to receive a locking screw 12 which extends through the alidade and is designed to assist in locking the support in adjusted position. These supports 2 and 3 are 85 designed to revolvably support either a telescope T or trunnions carried by said telescope accordingly as the instrument is used as a transit or as a builders lever.

The telescope T is of ordinary construction and is adapted to rest, by cylindrical bearings 13 and 14 secured thereon in any suitable manner, in the forked ends of the supports 2 and 3 as shown in Fig. 5 when the device is to be used as a builders level 90 and when in this position the telescope is held against tilting but is permitted to turn in said supports. The bearings 13 and 14 are here shown in the form of flanged collars secured to the telescope the same distance apart that the supports 2 and 3 are spaced on the alidade and the flanges of the collars are positioned to engage the inner or opposed faces of the forks of the supports 2 and 3 to hold the telescope against longitudinal movement while permitting it to revolve in said supports. Fixed to said telescope midway between said bearings 13 and 14 is a collar 15 having apertured ears 16 and 17 extending radially therefrom at one 105 110

edge thereof and at diametrically opposite points, said ears being preferably connected by a strip or flange 18, said flange and ears being preferably made integral with each other and with the collar 15. Sockets 19 are formed on the inner face of the strip 18 and are designed to receive studs on a coöperating element to be described. Removably secured to the collar 15 on the telescope are trunnions 20 and 21, which are connected at their inner ends by an integral yoke shaped or arcuate member 22. This yoke shaped trunnion connecting member has one face thereof cut out or recessed as shown at 23 a thickness equal to the thickness of the ears 16 and 17 and the flange 18 which are disposed in alinement with each other and with their opposite faces flush with each other. The concaved portion of the yoke member 22 is designed to closely embrace the collar 15 inside the flange 18 thereof and the inner face of said member is provided with laterally extending studs 24 which are designed to enter the sockets 19 on the flange 18 and thereby assist in securely holding said collar and yoke-shaped member together against movement relatively to each other, the ends of the ears 16 and 17 terminating adjacent the end walls of said recess 23. The yoke member 22 is provided at its opposite ends with screw threaded apertures 25 which are positioned to register with the apertures in the ears 16 and 17 when the parts are assembled and are designed to receive locking screws 26 for securely connecting the flanged collar 15 with the yoke-shaped trunnion connecting member. When said parts are connected as above described the trunnions 20 and 21 will be rigidly secured to the telescope and project in opposite directions therefrom in a plane at right angles to the axis of the telescope. Each of the trunnions 20 and 21 is provided near its outer or free end with a flange 27 and a cylindrical bearing surface 28 disposed outside said flange and the diameter of which is the same as that of the collars or bearings 13 and 14 carried by the telescope and these bearings 28 are spaced apart the same distance as the bearings 13 and 14 on the telescope to adapt them to be mounted in the supports 2 and 3 when the instrument is to be used as a transit.

From the above description it will be obvious that the trunnions 20 and 21 are made integral with each other and are rigidly but detachably secured to the telescope and that the instrument may be readily converted from a leveling instrument into a transit by simply releasing the locking levers 4 and 5 and lifting the telescope out of said supports 2 and 3 when the instrument is used as a leveling instrument and inserting the bearings 28 of the trunnions in said supports when the instrument will be ready for use as

a transit. When the instrument is used as a level, the telescope is mounted in the supports 2 and 3 as above described and it serves in all respects in the ordinary and long approved manner. The instrument being leveled the telescope may be turned in any required position and the telescope may be reversed and the alidade correspondingly reversed to reduce the errors due to imperfections of the instrument. The long bearings afforded by the instrument allow the accuracy of direction of leveling for which the ordinary builders level is greatly valued. 75

When it is desired to determine the vertical condition of a line as the wall of a building or to attain any other desired ends which require the telescope to be inclined, the levers 4 and 5 are opened and the telescope lifted from the supports 2 and 3 and the bearings 28 on the trunnions 20 and 21 inserted in said supports which insures the trunnions being disposed exactly at right angles to the axis of the telescope without any adjustment being necessary. The telescope is now free to rock on the bearings 90 carried by the trunnions to adapt it to sight an object at a considerable angle above or below the horizontal. Then by directing the telescope to any portion as the cornice of a building and locking the alidade in that position the line of sight of the telescope may be traversed up and down the line and its correctness determined with great accuracy. 95

It is to be understood that this telescope 100 is designed to carry the ordinary leveling tool which is not shown in the drawings.

I claim as my invention:—

1. A combined leveling instrument and transit comprising an alidade, forked supports mounted thereon, a yoke-shaped member having trunnions extending in longitudinal alinement with each other from the ends of said yoke member, one side face of said yoke being flattened, a telescope encircling collar having a plate for engagement with the flat face of said yoke, and means for locking said plate and yoke together. 110

2. A combined leveling instrument and transit comprising an alidade, forked supports mounted thereon, a yoke-shaped member having trunnions extending in longitudinal alinement with each other from the ends of said yoke member, one side face of said yoke being flattened, a telescope encircling collar having a plate for engagement with the flat face of said yoke, said plate and yoke carrying interlocking connecting elements, and means for locking said members together. 115

3. A combined leveling instrument and transit comprising an alidade, forked supports mounted thereon, a yoke-shaped member having trunnions extending in longitu- 130

dinal alinement with each other from the ends of said yoke member, one side face of said yoke being recessed, a telescope encircling collar having a flat face for engagement with the inner face of the recess of said yoke, lugs on said collar and means for locking said lugs and yoke together.

In testimony whereof I have hereunto set my hand in presence of two subscribing witnesses.

CHARLES L. PRANDONI.
